ORTHOPTIC INSTRUMENT

Alfred W. Sorenson, Racine, Wis., assignor to Visual Therapy Products Corporation, Racine, Wis., a corporation of Wisconsin

Filed Dec. 19, 1957, Ser. No. 48,956

Term of patent 14 years

(Cl. D57—1)

Fig. 1

Fig. 4

Fig. 3

Fig. 2

Fig. 1 is a front perspective view of an orthoptic instrument showing my new design;

Fig. 2 is a side elevational view thereof;

Fig. 3 is a front elevational view of the orthoptic instrument; and

Fig. 4 is a fragmentary view showing the viewer element of the instrument in elevation and illustrating the end thereof opposite that shown in Figs. 1 and 3.

I claim:

The ornamental design for an orthoptic instrument, substantially as shown and described.
